UNITED STATES PATENT OFFICE.

JOHN JOSEPH KANE, OF SIMSBURY, CONNECTICUT.

ANTIRATTLER ATTACHMENT FOR DOORS.

1,185,409.

Specification of Letters Patent. Patented May 30, 1916.

Application filed April 4, 1916. Serial No. 88,868.

To all whom it may concern:

Be it known that I, JOHN JOSEPH KANE, a citizen of the United States, residing at Simsbury, in the county of Hartford and State of Connecticut, have invented new and useful Improvements in Antirattler Attachments for Doors, of which the following is a specification.

This invention contemplates the provision 10 of an anti-rattler attachment for doors.

In automobile construction, it is a difficult matter to hingedly mount a door so that it will not rattle incident to the vibratory movements of the machine while in motion, 15 as the hinges are subjected to undue strain under such conditions, and which in a course of time permits the door to vibrate to the annoyance of the occupants of the car.

It is therefore the object of my invention 20 to provide in the nature of an attachment, a contrivance which can be associated with either the door or door casing, and which embodies a buffer susceptible of adjustment to compensate for any degree of play be- 25 tween the door and its casing, to prevent rattling of the door under any circumstances.

The use of the invention in connection 30 with an automobile door is sufficiently characteristic of its utility and admirably illustrates the invention, and will constitute one of its most useful applications. For this reason the description is addressed to the operation of the device with an automobile door, but it is to be understood however that 35 the device is susceptible for use in other capacities, and that its general application is contemplated by the claims.

In the drawing forming part of this specification like numerals of reference indicate 40 similar parts in the several views and wherein:

Figure 1 is a horizontal sectional view 45 through a door closed showing one application of the invention. Fig. 2 is a side elevation of the device removed from the door. Fig. 3 is a front elevation. Fig. 4 is a perspective view of the buffer and its carrier.

Before entering into a detail description 50 of what is herein shown I desire to have it understood that the contrivance forming the subject matter of my invention can be associated with either the door or door casing in the most advantageous position. As herein shown however, the door indicated at 10 is rabbeted to provide a pocket for the reception 55 of the device, which preferably consists

of an attaching plate 11 secured to the door in any suitable manner, and provided with an elongated longitudinally disposed slot 12, through which the buffer as a whole is 60 adapted to slide. The buffer as shown in this instance embodies a carrier or receptacle of a configuration to accommodate the buffer element 14 which may be of any suitable cross sectional configuration, but which as 65 herein shown is of rectangular outline. The receptacle 13 is preferably formed from a single piece of material such as metal, and having the marginal edges of the base projecting an appreciable distance beyond the 70 walls of the receptacle as at 15, to provide a stop adapted to abut against one side of the plate 11 to limit the adjustment of the buffer to a projected position through the slot 12. The buffer element 14 may be constructed 75 from any suitable material preferably rubber and snugly fitted within the receptacle as shown.

The buffer in its entirety together with the means employed for adjusting the same is 80 wholly disposed within the pocket defined by rabbeting the door or casing with which it is adapted to be associated, with the buffer element 14 projecting a slight distance beyond the jam of the door or casing so as to hold these parts fixed relatively when the door is in its closed position. However should for any reason the door obtain play between the casing, the buffer can be proportionately adjusted to eliminate such play 85 and thereby hold the door immovable and closed under any condition. While this adjustment of the buffer can be accomplished 90 in many ways, I preferably employ an arm 95 pivoted between spaced apertured lugs 17 projecting from the rear side of the plate, the arm being pivoted at a point adjacent one end so that this end indicated at 18 will project a slight distance beyond the pivot lugs 17. The arm is slightly curved longitudinally terminating at its opposite end to provide an offset portion 19 adapted to engage the buffer carrying the receptacle 13. Adjustably mounted through an opening 100 adjacent one end of the attaching plate 11 is a set screw 20 adapted to engage the projecting end 18 of the arm, so that upon adjustment of the screw in one direction, rocking movement will be imparted to the arm 16 which operates to move the buffer 105 through the slot 12 in the plate 11 the requisite distance to compensate for any play be- 110

tween the door and its casing with a view of holding the door immovable in closed position. It will be noted that the offset portion 19 of the arm engages the buffer carrying 5 receptacle centrally of the bottom thereof to evenly distribute the pressure exerted thereon, whereby the buffer in its entirety is evenly moved through the slot so that the buffer element 14 will engage its object 10 throughout its entire length, with a view of effectively holding the door against vibratory movements incident to the travel of the machine, and thereby relieve the hinges of undue strain, to which they are generally subjected under such conditions. The device is both simple in its construction and 15 very efficient for the purpose intended.

While it is believed that from the foregoing description the nature and advantages 20 of the invention will be readily apparent, I desire to have it understood that the same is merely illustrative of one embodiment of the invention to which I do not limit myself, and that changes in the construction and 25 arrangement of parts may be resorted to when desired as fall within the scope of what is claimed.

What is claimed is:—

1. An anti-rattler attachment for doors 30 comprising an attaching plate having an opening therein, a buffer capable of sliding movement through said opening, an arm

mounted upon the plate for rocking movement and having one end normally engaging said buffer, and means for adjusting 35 said arm to project the buffer through said opening.

2. An anti-rattler attachment for doors comprising an attaching plate having an opening therein, a buffer capable of sliding 40 movement through said opening, an arm mounted upon the plate for rocking movement and having one end normally engaging said buffer, means for adjusting said arm to project the buffer through said opening, and means for limiting the movement 45 of the buffer through said opening.

3. An anti-rattler attachment for doors comprising an attaching plate having an opening therein, a buffer capable of sliding 50 movement through said opening, an arm mounted for rocking movement on said plate and having one end normally engaging said buffer, and said set screw adjustably associated with the plate and engaging the 55 opposite end of said arm to rock the latter, whereupon said buffer is projected through said opening.

In testimony whereof I affix my signature in presence of two witnesses.

JOHN JOSEPH KANE.
